CLAIM

The ornamental design for a container lid, as shown and described.

DESCRIPTION

FIG. 1 is a top perspective view of a container lid showing a new design;

FIG. 2 is bottom perspective view thereof;

FIG. 3 is a top plan view thereof;

FIG. 4 is a bottom plan view thereof; and,

FIG. 5 is another top perspective view showing the container lid mounted to a container.

The dashed lines shown in the drawings are for environmental purposes only and form no part of the claimed design.

1 Claim, 5 Drawing Sheets(56)
